CONTAINER

Otto J. Lozo, Chicago, Ill.

Application September 24, 1934, Serial No. 745,325

1 Claim. (Cl. 206—48)

This invention relates to a container and more particularly to a combination container for matches, cigarettes and the like.

An object of the invention is to provide a simple and ready means for attaching a folder containing matches to a package of cigarettes or the like. Other specific objects and advantages will appear as the specification proceeds.

The invention is illustrated, in preferred embodiments, by the accompanying drawing, in which—

Figure 1 is a perspective view of a package and cover equipped with means for receiving a match holder; Fig. 2, a similar perspective view showing the holder secured to the cover of the box or package; Fig. 3, a sectional view, the section being taken as indicated at line 3 of Fig. 2; and Fig. 4, a perspective view of a package equipped with a modified form of means for securing the match holder to the package.

In the illustration given in Figs. 1 to 3, inclusive, A designates a cigarette box or package; B, a cover of "Cellophane" or the like; and C, a match holder secured to the "Cellophane" cover B.

The cigarette box or case A may be of any suitable construction. It will be understood that the box may contain, instead of cigarettes, small cigars or the like. The cover B may be formed of "Cellophane", gelatin or other covering material which is desired as a protection for the box, as well as for excluding air from the contents of the package. As illustrated more clearly in Fig. 1, I form slots 10 on one or two sides of the cover B, and in order to prevent the passage of air through such slots, I provide a temporary cover 11 for each slot. Preferably, the cover 11 is cemented to the covering B by a pressure sensitive adhesive which cooperates with the cover 11 to seal the slot 10 while at the same time permitting the ready removal of cover 11. If desired, one end of each strip 11 may be curled slightly away from the cover B to enable it to be grasped readily to effect the removal of the strip.

The match holder C is of well known construction. It consists of a paper body 12 forming substantially a loop encircling the matches 13. The loop is provided with a short base portion equipped with a roughened surface 14 against which the matches may be struck for ignition. The flap 14 also provides a latch recess into which the lower front portion 15 of the match cover may be inserted for closing the loop. As in the usual construction, matches are secured to the bottom U-shaped portion 16 of the folder

12, so that the front and rear portions of the folder are free from attachment and may be folded about the matches.

In the operation of the container construction, as shown in Figs. 1 to 3, the purchaser or seller at the time of the sale, may grasp the cover strips 11 and tear them away to free the slots 10. The free end 15 of the match holder may then be inserted through the bottom slot and extended between the cover and the outer wall of the box and then extended forwardly through the upper slot 10, as shown more clearly in Fig. 3. The outer flap of the folder may then be drawn downwardly into the latch recess behind the roughened surface 14. By this means, the match holder can be quickly and securely attached. In view of the fact that the user opens the package of cigarettes substantially at the time the matches are attached to the cover B, there is no necessity for excluding air any further.

In the modification shown in Fig. 4, the cover B is equipped with a loop 17 formed of "Cellophane" or other similar material. Adhesive or other suitable means may be employed to secure the inner folded ends 18 of the loop to the cover. With this construction, the free flap portion of the match holder may be readily inserted through the loop and folded over into the position shown in Fig. 3. This construction has the advantage that there is no necessity for breaking the seal of the package to attach the match holder. If desired, the match container may be secured to the package cover B at the factory.

It will be observed that in the operation of each of the modifications shown, the match holder does not enter the cigarette container A, so that there is no danger of injury to the cigarettes during the attachment operation. Attachment is rendered easy by virtue of the fact that the folder tip, during the inserting operation, slides against the smooth wall and not against the contents of the package. While it may be possible to attach the match holder directly to the box, this is less desirable because it permits the air to enter the box and also because of the difficulty in slipping the free end of the match holder through the walls of the box without injuring the cigarette papers.

When a folder of matches has been used up, the folder may be readily withdrawn from each of the modifications shown and a new folder substituted; or, if desired, the match folder may be quickly stripped from the box together with the "Cellophane" cover.

Instead of attaching the match folder as illustrated in Figs. 2 and 3, the forward free flap of the folder may be turned back upon itself and the back portion of the folder inserted through the 5 slots or through the loop, thus exposing the matches. The first described mode of attachment is preferred, however, because the front folder can be placed over the matches while one of the matches is being struck, thus preventing 10 ignition of the remaining matches.

While in the illustrations given, I have disclosed two means of attaching the match holder to the cigarette cover, it will be obvious that other means may be employed without departing 15 from the spirit of my invention. The foregoing

detailed description has been given for clearness of understanding only, and no unnecessary limitations should be understood therefrom, but the appended claim should be construed as broadly as permissible, in view of the prior art.

5

I claim:

In combination, a package for cigarettes or the like, a cover therefor, said cover being provided with a pair of spaced slots adapted to receive the loop portion of a match holder when the 10 same is extended therethrough, and a pair of sealing strips secured by pressure sensitive adhesive in sealing relation to said slots.
